CLAIM

The ornamental design for a tablet stand, as shown and described.

DESCRIPTION

FIG. 1 is a perspective view of the tablet stand according to a first embodiment.

FIG. 2 is a front view of the tablet stand of FIG. 1.

FIG. 3 is a rear view of the tablet stand of FIG. 1.

FIG. 4 is a side view of the tablet stand of FIG. 1.

FIG. 5 is a side view of the tablet stand of FIG. 1.

FIG. 6 is a top-down view of the tablet stand of FIG. 1.

FIG. 7 is a bottom-up view of the tablet stand of FIG. 1.

FIG. 8 is a perspective bottom view of the tablet stand of FIG. 1.

FIG. 9 is a perspective view of the tablet stand according to a second embodiment.

FIG. 10 is a front view of the tablet stand of FIG. 9.

FIG. 11 is a rear view of the tablet stand of FIG. 9.

FIG. 12 is a side view of the tablet stand of FIG. 9.

FIG. 13 is a side view of the tablet stand of FIG. 9.

FIG. 14 is a top-down view of the tablet stand of FIG. 9.

FIG. 15 is a bottom-up view of the tablet stand of FIG. 9; and,

FIG. 16 is a perspective bottom view of the tablet stand of FIG. 9.

The broken lines illustrate portions of the tablet stand and form no part of the claimed design.

The four right trapezoids creating an octagon design forming part of the claimed design in FIG. 3 is a registered trademark of JPMORGAN CHASE BANK, N.A.

1 Claim, 14 Drawing Sheets
